ABSTRACT OF THE DISCLOSURE

A highly sensitive assay technique for primary amine-containing compounds utilizes fluorescence produced by the interaction of the primary amine compound with ninhydrin and an aryl alkyl aldehyde. A preferred aryl alkyl aldehyde for the assay technique is phenylacetaldehyde. The assay is useful for the qualitative and quantitative determination of amino acids, peptides, proteins and any other organic compounds containing a primary amino moiety.

BACKGROUND OF THE INVENTION

The use of ninhydrin as a colorimetric reagent for the detection and assay of amino acids, amines and peptides has been known in the art for nearly sixty years. More recently, the ninhydrin color reaction has found extensive application in conjunction with the newly developed amino acid analyzers for the automated microanalysis of amino acid compositions of protein hydrolysates. By the use of micro techniques, it has been possible to apply the colorimetric ninhydrin procedure at the nanomole level. However, this figure represents the limit of sensitivity of the colorimetric technique.

It has also been known in the prior art that ninhydrin can yield highly fluorescent products with amine-containing compounds. For example, McCaman and Robins in their paper in *J. Lab. Clin. Med.* 59, 885 (1962), disclosed a fluorometric assay technique that utilizes ninhydrin in the determination of serum phenylalanine. Close has reported on a study related to the fluorescence obtained by incubating amino acids or amines with ninhydrin and n-butyraldehyde (see fluorescence assay in *Biology in Medicine* by S. Udenfriend, Academic Press, New York (1969) at p. 196).

BRIEF DESCRIPTION OF THE INVENTION

The present invention relates to an improved assay method for the determination of organic compounds containing a primary amino group utilizing fluorescence techniques. In particular, the invention is concerned with a process which involves reacting an organic compound containing a primary amino group with a certain class of aldehydes and ninhydrin to quantitatively produce a highly fluorescent material which can be detected by standard fluorometric techniques and can yield both qualitative and quantitative data relating to said primary amine. An important feature of this invention is that it makes possible the detection of much smaller quantities of amines, amino acids, and peptides than have heretofore been possible utilizing standard colorimetric and fluorometric techniques.

A major aspect of this invention is the utility for fluorometric assays in solution. In such a process a mixture of the primary amine-containing compound, the aldehyde and ninhydrin in an inert solvent containing a pH buffer is heated and the fluorescence is then measured by standard fluorometric techniques. Quite unexpectedly, it has been found that aryl alkyl aldehydes give complexes that are very highly fluorescent. The aryl alkyl aldehydes comprehended by this invention are defined by the formula

2

wherein Ar is an aromatic residue and n is an integer having a value of from 1 to 8. Aldehydes wherein n has a value of from 1 to 3 are particularly useful. Preferred aryl alkyl aldehydes are those where n is 1 and the aromatic residue is phenyl or alkyl substituted phenyl, e.g. phenylacetaldehyde or 4-methyl phenylacetaldehyde. Phenylacetaldehyde is especially preferred.

For example, under identical reaction conditions, the fluorescence produced by using phenylacetaldehyde as compared with that produced by using n-butyraldehyde, a reagent used in previous fluorometric assays, is at least 3 to 30-fold greater depending upon the pH. A wide variety of primary amine-containing compounds can be assayed by the present technique. Such classes of compounds include primary amines, e.g. ethylamine, ethanolamine, tryptamine, dopamine, norepinephrine, etc.; α -amino acids containing a primary amino group, e.g. glycine, alanine, leucine, valine, etc. and peptides containing a primary amino group e.g. insulin, angiotensin, leucylalanine, etc.

It is important that ammonia, secondary and tertiary amines, and compounds which contain an amino group as part of a larger functionality, such as an amide, guanidine or urethane residue, afford complexes which have little or no fluorescence and which, thus, do not interfere with the assay for primary amine-containing compounds.

The proportions of the reactants used are not broadly critical but normally it is preferred to use a large excess of the aldehyde and ninhydrin with respect to the amine being determined so that the fluorescent product is quantitatively formed. It is generally preferred to use an excess of ninhydrin as compared with aryl alkyl aldehyde. A ten-fold excess is conveniently utilized.

The incubation temperature is also not critical and can be carried out over a range of from about 40° C. to about the boiling point of the reaction medium. It is preferred, however, to utilize a temperature range of from about 55° C. to about 65° C. The time involved in the incubation varies extensively with the substrate and the pH but is generally in the range of from about 5 minutes to about 4 hours. The pH of the incubation medium is normally between about 4 and 9. However, a pH range of from about 6 to 8 is especially preferable.

The pH is controlled by the addition of a buffer to the reaction medium. Suitable buffers are phosphate buffers and others known in the art. The choice of exact pH for any particular assay is dependent upon many factors such as the substrate and the type of assay being performed. For example, at pH values around 6.0 one observes a higher fluorescence for amines and peptides than for neutral amino acids. Although, in general, the absolute intensity of the fluorescence is slightly lower at the lower pH, it offers considerable specificity for the determination of amines and peptides. As one increases the pH, going for example, from pH 6 to pH 8, the fluorescence values of amino acids are increased relative to that of amines and peptides. Also, as the pH is increased the incubation time can be decreased.

The limits of sensitivity for the assay procedure of the present invention can be determined for a variety of substrates and compared with those for the standard colorimetric ninhydrin assay procedure of Moore and Stein, *J. Biol. Chem.* 176, 367 (1948). The smallest amount which can be determined by the present method is in the range of 10^{-10} to 10^{-11} moles; whereas for the colorimetric method 10^{-9} moles was the smallest amount detectable. Therefore, the fluorescent ninhydrin aldehyde method of the present invention is at least 10 to 100 times more sensitive than the ninhydrin color reaction.

Fluorometric detection has an inherent advantage over colorimetric detection in that in the former method an absolute quantity is measured, whereas in the latter method a difference between two measured values is determined, thus reducing the accuracy and limiting the minimum amount detectable. In essence, the limiting factor for a fluorometric assay is the sensitivity of the detection system, i.e. the instrumentation.

The assay procedure of the present invention has been automated to continuously detect, qualitatively and quantitatively, primary amine-containing compounds in a sample stream. It is particularly useful to employ, as a sample stream, the effluent from a chromatographic system, for example, a chromatographic column for the separation of amino acids.

In such a procedure, the sample stream is introduced into the automated analyzer at a constant rate and streams of reagents (ninhydrin, aryl alkyl aldehyde and buffer) are added thereto. A suitable means for controlling the addition of the reagents and the flow rate of the sample stream is by use of a proportionating pump. After the reagents are added to the sample stream, they are thoroughly mixed with the sample stream by, for example, passing through a mixing coil. The mixture is then heated at the appropriate temperature for a predetermined length of time to produce fluorescent substances. The heating is conveniently done by passing the mixture through a coil of fixed length, inserted in a constant-temperature heating bath, so that the residence time in the heated coil is known. The solution, after leaving the heating coil, is cooled and passed into a continuous flow cell of a fluorophotometer where it is fluoresced and the fluorescence continuously detected. If desired, the detector of the fluorophotometer may be linked to a suitable recording, data display or print-out device.

Another use for the assay procedure of the present invention is for the qualitative and quantitative determination of primary amine-containing compounds in a mixture by a technique involving automated, successive sampling of a multiplicity of samples.

In such a method, a fixed volume of a sample solution is introduced by utilizing, for example, a probe which dips into the sample solution. The sample stream thus introduced is processed as for the automated analyzer described above. The sample solutions are separated from one another within the flowing stream by methods generally used, for example, solvent or gas bubbles. If the bore of the tubing carrying the flowing stream is sufficiently small, no additional means for separating the sample solutions from one another is necessary, since capillary action will prevent intermixing.

The automated presentation of sample solutions for introduction into the analyzer can be accomplished by techniques generally used in the art.

The automated assay procedure of the present invention can also be used in closed-loop process control systems to monitor the level of primary amine-containing compounds in a reaction medium and automatically control the reaction process by methods such as that described by Hana et al. in U.S. Pat. 3,306,096.

Another major use for the present invention is for the detection of primary amine-containing compounds on paper or thin layer chromatograms. In such a system, the sample is applied to the paper or thin layer plate and developed in the normal manner. The paper or plate is then sprayed with a solution containing ninhydrin, the aryl alkyl aldehyde and the pH buffer as described above for the solution assays. The paper or plate is then heated and the fluorescent spots measured. Instead of using an excess of ninhydrin over the aryl alkyl aldehyde as in the solution assays, it is preferable for the paper and thin layer chromatographic assays to use an excess of the aryl alkyl aldehyde over ninhydrin. A molar ratio of aryl alkyl aldehyde to ninhydrin of about 3 to 1 is especially preferable. In this manner, the fluorescent product is formed

in high yields. The choice of solvent, pH, temperature and time is controlled by the same considerations as discussed above for the solution assays. The techniques used for paper and thin layer chromatograms prior to the detection procedure (e.g., spotting of the sample, development of the chromatogram, etc.) are those normally employed in the art.

The particular advantages of the present invention are enumerated below. First, the sensitivity of this method is at least 10 to 100 times greater than commonly used colorimetric methods and 3 to 30 times greater than fluorometric methods for amine assay. Secondly, this method has a wide scope and has been applied to a large variety of primary amines, amino acids and peptides. A third advantage of the present method is that it is readily suited to automation since the fluorescence is proportional to the concentration of amine substrate over a wide range of concentration. The present technique achieves maximum sensitivity as it starts with a reagent which is not fluorescent but which yields fluorescence only on interaction with primary amine-containing compounds. The fact that ammonia does not react in the present process is of great importance since ammonia is usually present in substantial amounts in protein hydrolysates and it is known that traces of ammonia in the atmosphere can limit the usefulness of known colorimetric and fluorometric methods for amine detection.

Another advantage of this method is that at low pH values, particularly about pH 6, far more fluorescence is obtained with peptides than with amino acids. Peptides, particularly large peptides which yield little color with the classical ninhydrin procedures can be identified by the present method. Comparison of proteins by finger-printing methods usually requires several milligrams of protein to detect all the peptides. By utilizing the procedure of the present invention one can accomplish the same results using only microgram quantities of the protein. Automated fluorometric assays of peptides obtained from digestion of microgram quantities of proteins make it possible to carry out genetic studies even on the small amounts of protein obtained from a single laboratory animal.

Another important application is in the detection of small amounts of physiologically active peptides in tissues. In addition to the utility for identifying known peptides by assay, the method of the present invention is suitable for the detection of new peptides whose biological roles or activities have not yet been ascertained.

In the examples which follow, all temperatures are expressed in degrees centigrade.

EXAMPLE 1

General procedure for fluorometric assay in solution

To a 13 x 100 mm. test tube were added 2.0 ml. of 0.2 M phosphate buffer (pH 6, 7, or 8) 0.2 ml. of aqueous ninhydrin (50 mM.), 0.1 ml. of aqueous sample solution (generally 10^{-4} to 10^{-2} mM.) and finally 0.1 ml. of phenylacetaldehyde in ethanol (10 mM.). After mixing thoroughly, the tubes were covered with aluminum foil and transferred to a 60° water bath for a suitable incubation period; 15 min. at pH 8.0, 60 min. at pH 7.0 and 120 min. at pH 6.0. The tubes were then cooled in an ice bath for a few minutes, kept at room temperature for 10 minutes and fluorescence measured within 1 hour (using an Aminco-Beckman fluorophotometer with a 1 cm. cell). Excitation was set at 390 m μ and emission at 490 m μ .

50	100	100	
+	+	+	10
+	-	+	1
-	+	+	1

Fluorescence is presented in terms of arbitrary units. The value under each reactant represents m_μmoles contained in 2.4 ml. of reaction mixture. The general procedure of Example 1 was used to develop and measure the fluorescence.

EXAMPLE 3

This example illustrates the effect of various aldehydes in producing fluorescence with a peptide and ninhydrin.

Aldehyde	Relative fluorescence at pH		
	6.0	7.0	8.0
Formaldehyde	11	0	0
Acetaldehyde	3	7	7
n-Butyraldehyde	34	521	349
Isobutyraldehyde	11	1	0
Glutaraldehyde	22	21	0
Benzaldehyde	14	0	0
trans-Cinnamaldehyde	13	1	0
Phenylacetaldehyde	982	1,611	1,609
Diphenylacetaldehyde	0	0	0
4-methylhydroxyaldehyde	0	0	0
4-methylphenylacetaldehyde	986	0	0
3,4-dimethoxyphenylacetaldehyde	0	0	0

Twenty μ l. of each aldehyde in ethanol solution (10 mM.) was added to a mixture containing 40 μ l. of leucylalaninylglycylvaline (1.25 mM.), 75 μ l. of ninhydrin (30 mM.) and 200 μ l. of 0.6 M phosphate buffer at the pH indicated. After incubating for 90 minutes at 60° the samples were cooled to room temperature and fluorescence was measured as described in Example 1.

EXAMPLE 4

This example illustrates the difference in fluorescence obtained with glycine and a series of glycine peptides.

Compound	Fluorescence at pH		
	6.0	7.0	8.0
Glycine	81	618	800
Di-glycine	514	1,159	796
Tri-glycine	509	1,048	710
Tetra-glycine	504	997	620
Penta-glycine	500	970	580

A mixture of 20 μ l. of ethanolic phenylacetaldehyde (10 mM.), 37.5 μ l. of an aqueous solution of each peptide (13.3 mM.), 75 μ l. of aqueous ninhydrin (30 mM.) and 187.5 μ l. of phosphate buffer (0.6 M, pH 6.0, 7.0 or 8.0) was incubated for 30 minutes at 60° and diluted with 2.0 ml. of aqueous sodium carbonate (15 mM.). The fluorescence was measured as in Example 1.

20	Relative fluorescence intensity								
	pH 6.0			pH 7.0			pH 8.0		
	Lys	Gly	Leu-Ala	Lys	Gly	Leu-Ala	Lys	Gly	Leu-Ala
15				740	745	1,096	740	1,216	1,607

One m_μmole of each compound was used and fluorescence was developed by the procedure described in Example 7.

ample 1 at pH 7. All measurements were made with excitation at 390 m μ and emission at 480 m μ .

EXAMPLE 8

This example illustrates the difference in sensitivity between the fluorescence assay of the present invention and the standard colorimetric assay.

Compound	Absorbance		Relative fluorescence	
	Observed	Reagent minus blank	Observed	Reagent minus blank
Glutamic acid.....	0.079	0.036	254	153
Glycine.....	0.081	0.038	916	815
Lysine.....	0.083	0.040	904	803
Glycylglycine.....	0.077	0.034	1,456	1,355
Leucylalanine.....	0.092	0.049	2,118	2,017
Tyramine.....	0.075	0.032	1,128	1,027
Hisamine.....	0.070	0.027	948	847
Blank.....	0.043	-----	101	-----

Equal amounts (5 μ moles) of substrate were used in determination by colorimetric technique (procedure of Moore and Stein) and the technique of the present invention as illustrated in Example 1 at pH 7. It can be seen that in the colorimetric method the corrected absorbance is of the same order of magnitude as the blank reading, thus introducing a large probability of error; whereas for the fluorometric assay the corrected fluorescence is generally an order of magnitude greater than the blank, thus allowing for more accurate determinations and the possibility of detecting smaller amounts of substrate.

EXAMPLE 9

Varying amounts of glutamic acid, glycine, leucylalanine and tyramine in 1 μ l. were spotted on paper or silica gel thin layer plates. After development with solvents and drying, the paper or plate was sprayed with a solution of phenylacetaldehyde (15 mM.) and ninhydrin (5 mM.) in ethanol. The ethanol was allowed to evaporate at room temperature and the chromatogram was then sprayed with 0.2 M phosphate buffer, pH 8.0. The wet chromatogram was then heated at 60° for 15 minutes and after cooling was examined under ultraviolet lamp (366 m μ). With the above method, the detection limit for glutamic acid was 10^{-10} mole; for glycine, leucylalanine and tyramine, 10^{-11} mole. With the normal Ninhydrin color reaction, the detection limit was 10^{-10} mole for all four.

EXAMPLE 10

Ten μ l. of an amino acid standard solution (containing 1μ mole/ml each of 20 common amino acids and ammonia) was applied to a 0.9 cm. x 55 cm. column of 7.5% cross-linked sulfonated styrene copolymer resin (Beckman UR-30 resin for the separation of acidic and neutral amino acids) and developed at 70 ml./hr., first with 117 ml. 0.2 N sodium citrate, pH 3.25, then with 140 ml. 0.2 N sodium citrate, pH 4.3. The starting temperature was 45° , and after 30 minutes it was raised over a 1 hour-period to 55° and held at this temperature throughout the remainder of the experiment. The effluent from the column was split into two streams in the ratio of 9:1. The larger of the streams was passed through a Beckman Model 120-C amino acid Analyzer in the normal fashion. The smaller stream, flowing at 0.1 ml./min., was mixed with 0.3 ml./min. of a stream of a solution prepared by mixing 2.67 g. ninhydrin, 180 mg. phenylacetaldehyde, 300 ml. of ethanol and 150 ml. water, and a stream of 0.2 M sodium phosphate buffer, pH 7.5, flowing at 2.0 ml./min. These flow rates were controlled by means of a proportionating pump. The total flow rate after mixture was 2.4 ml./min. An air bubble was introduced approximately every 1.5 seconds to separate the stream into small segments. The flowing stream was passed through a short mixing coil and then into a coil inserted in a heating bath maintained at 65° . The total

time for the stream to pass through this heating coil was 30 minutes. After coming out of the heating coil, the stream was cooled to 17° C. and introduced into a 1 cm. Aminco half cell provided with a debubbler. Seventy-five percent of the flow passed through the cell (1.8 ml./min.) and 25% was removed in the debubbler. The flow cell was contained in an Aminco Fluoro-Microphotometer equipped with an 85 watt General Electric mercury vapor lamp, an Aminco No. 7.51 filter for excitation, an aperture plate set at maximum excitation and an Aminco No. 4 filter for detection. The fluorophotometer was operated at a high voltage setting of 40, a sensitivity setting of 50% and an attenuation setting of 3% full scale (corresponding to 3 mv. for full scale reading). The output of the fluorophotometer was coupled to a Beckman 10 inch recorder with a chart speed of 0.1 inch/min.

The recorder used in the Beckman Amino Acid Analyzer for the normal colorimetric analysis was operated at a 5 mv. full scale sensitivity and recorded the normal 570 $\mu\mu$ output of the colorimeter. The chart speed was 0.1 inch/min.

A parallel experiment was run using a 0.9 cm. x 5 cm. column of 8% cross-linked sulfonated styrene copolymer resin (Beckman PA-35 resin for separating basic amino acids).

The attached drawing shows the recorder tracings made under the above-described conditions. The first run (shown at the left) is for the basic amino acids using the PA-35 column. The second run is for the neutral and acidic amino acids using the UR-30 column.

The chart below presents the data of the attached drawing in tabular form. The relative areas under each peak recorded by both the colorimetric and fluorometric methods is presented. These areas have been corrected for differences in the amount of sample being measured by each method and difference in the attenuation of the recorders used. The figures as presented represent the integrated response of each detector under identical conditions produced by equal amounts of each amino acid.

		Relative area under peaks of drawing—corrected	
Amino acid		Colorimetric	Fluorometric
5 OH-lysine		252	900
Lysine	—	150	760
Histidine	—	145	1,350

I claim:

1. A method for determining a primary amine-containing compound in a mixture containing same which method comprises contacting said mixture with ninhydrin and an aryl alkyl aldehyde selected from the group consisting of phenylacetaldehyde and 4-methylphenylacetaldehyde heating the above treated mixture to produce a fluorescent substance therein fluorescing said substance and detecting the fluorescence.
  2. The method of claim 1 wherein said treatment is done in solution.
  3. The method of claim 2 wherein the aryl alkyl aldehyde is phenylacetaldehyde.
  4. The method of claim 2 wherein the pH of the solution is between 6 and 8.

5. The method of claim 2 wherein the molar amounts of ninhydrin and aryl alkyl aldehyde are in excess as compared with the molar amount of primary amine-containing compound.

6. The method of claim 2 wherein the primary amine-containing compound is an α -amino acid.

7. The method of claim 2 wherein a fluorophotometer is utilized for fluorescing said substance.

8. The method of claim 2 wherein the concentration in solution of a known primary amine-containing compound is quantitatively determined by (a) determining the fluorescence produced by a measured concentration of said amine, (b) determining the fluorescence produced by the unknown concentration of said amine, and (c) obtaining the unknown concentration by multiplying the known concentration by the ratio of the unknown to the known fluorescence values.

9. The method of claim 2 wherein the primary amine-containing compound is a polypeptide.

10. The method of claim 9 wherein the polypeptide is selectively determined in a pH range of 6.0 to 7.0.

11. The method of claim 1 wherein the primary amine-containing compound is present on at least a portion of a surface of a paper or thin-layer chromatographic medium and the ninhydrin and aryl alkyl aldehyde are applied to said surface of said chromatographic medium.

12. The method of claim 11 wherein the aryl alkyl aldehyde is phenylacetaldehyde.

13. The method of claim 11 wherein the pH of the chromatographic medium is kept between 6 and 8.

14. The method of claim 11 wherein the molar amounts of ninhydrin and aryl alkyl aldehyde are in excess as compared with the molar amount of the primary amine-containing compound.

15. The method of claim 14 wherein the aryl alkyl aldehyde is present in a 3-fold molar excess as compared with the ninhydrin.

16. The method of claim 14 wherein the primary amine-containing compound is an α -amino acid.

17. The method of claim 14 wherein the primary amine-containing compound is a polypeptide.

18. The method of claim 1 wherein the primary amine-containing compound is determined by an automated procedure which comprises (a) continuously contacting a sample stream containing said primary amine-containing compound in solution with a fixed proportion of ninhydrin and aryl alkyl aldehyde, (b) continuously passing the mixture obtained in step (a) through a heating zone to produce a stream containing a fluorescent substance, (c) passing the solution obtained in step (b) at constant rate through a flow cell of a fluorophotometer whereby any fluorescent material present is fluoresced and detected.

19. The method of claim 18 wherein the sample stream is at least a portion of the effluent of a chromatographic column.

20. The method of claim 18 wherein the pH of the solution being fluoresced is maintained between 6 and 8.

21. The method of claim 18 wherein the primary amine-containing compound is an α -amino acid.

22. The method of claim 18 wherein the primary amine-containing compound is a polypeptide.

23. The method of claim 18 wherein the total amount of a specific known primary amine-containing compound present in the sample stream is quantitatively determined by (a) determining the total fluorescence produced by a known quantity of said primary amine-containing compound, (b) determining the total fluorescence produced by the unknown quantity of said primary amine-containing compound under the same conditions as step (a), and (c) obtaining the unknown amount by multiplying the known quantity by the ratio of the unknown to the known total fluorescence.

24. The method of claim 18 wherein the aryl alkyl aldehyde is phenylacetaldehyde.

25. The method of claim 24 wherein the molar amounts of ninhydrin and phenylacetaldehyde are in excess as compared with the molar amount of primary amine-containing compound.

26. A reagent for the determination of primary amine-containing compounds consisting essentially of a solution of ninhydrin and an aryl alkyl aldehyde selected from the group consisting of phenylacetaldehyde and 4-methylphenylacetaldehyde in an inert organic solvent.

27. The reagent of claim 26 wherein the aryl alkyl aldehyde is phenyl acetaldehyde.

28. The reagent of claim 27 wherein the ninhydrin is present in about a 10-fold molar excess as compared with the phenylacetaldehyde.

29. The reagent of claim 27 wherein the phenylacetaldehyde is present in about a 3-fold molar excess as compared with the ninhydrin.
